UNITED STATES PATENT OFFICE.

CHARLES N. SCHNEIDER, OF NEW YORK, N. Y.

BRIDLE-STRAP-ATTACHING TIP.

Application filed November 23, 1923. Serial No. 676,603.

To all whom it may concern:

Be it known that I, CHARLES N. SCHNEIDER, a citizen of the United States, and a resident of the city of New York, borough 5 of Manhattan, in the county and State of New York, have invented a new and improved Bridle-Strap-Attaching Tip, of which the following is a full, clear, and exact description.

10 This invention relates to improvements in piano actions and has particular reference to a means for attaching the bridle-strap to the back stop shank.

Heretofore considerable difficulty has been 15 experienced in replacing a broken bridle-strap as it is the usual custom to remove the back stop shank from the hammer butt and insert the extremity of the new bridle-strap in the opening and then reinser the 20 back stop shank.

It is therefore the main aim of the present invention to overcome the above recited objections and disadvantages by providing an attaching tip for the bridle-strap which 25 obviates the necessity of removing the back stop shank when the original bridle-strap is replaced by a new one.

Another object in view is to provide an 30 attaching tip which is engageable in the usual opening formed in the back stop, which tip operates to securely anchor the bridle-strap and which tip further functions as a buffer element in case of the loss of the usual felt buffer which is carried by the back stop.

35 As a still further object the invention contemplates an improved form of attaching tip which is comparatively simple in its construction and mode of attachment, which is inexpensive to manufacture and which is thoroughly reliable and highly efficient in its purpose.

With the above recited and other objects in view, the invention resides in the novel 45 construction set forth in the following specification, particularly pointed out in the appended claims and illustrated in the accompanying drawings, it being understood that the right is reserved to embodiments other 50 than those actually illustrated herein to the full extent indicated by the general meaning of the terms in which the claims are expressed.

In the drawings:—

55 Figure 1 is an elevation of a portion of the piano action illustrating the improved

form of bridle-strap attaching tip in applied position.

Fig. 2 is a face view of the back stop with the improved bridle-strap attaching means 60 in position.

Fig. 3 is a fragmentary enlarged sectional view of the tip in position in the back stop opening.

Fig. 4 is a detail perspective view of the 65 yieldable sleeve of the attaching tip removed.

Fig. 5 is a perspective view of a repair bridle-strap with the attaching tip connected thereto and illustrating the shape of 70 the tip prior to its association with the back stop.

Referring to the drawings by characters of reference, 10 designates the hammer butt of a piano action, 11 the back stop and 12 75 the back stop shank, the said back stop being provided with the usual opening 13 therethrough for the passage of the bridle-strap 14. It is the usual practice to insert the extremity of the bridle-strap 14 in the 80 opening 15 of the hammer butt which receives the back stop shank 12. However, when the bridle-strap wears and breaks it necessitates the removal of the back stop shank in order to insert the extremity of a 85 new bridle-strap therein. This necessitates the removal of a number of parts of the action, which not only consumes time and necessitates additional labor, but puts the piano out of action until the glue which 90 normally retains the back stop shank in the opening 15, has dried. The attaching tip constituting the present invention consists of a headed element 16 having a shank 17 95 which is preferably threaded and a yieldable sleeve 18 which is preferably of rubber adapted to snugly embrace and cover the shank 17. The terminal 19 of the bridle-strap 14 is inserted between the shank and the sleeve to constitute a repair bridle-strap 100 for replacing a worn or broken one. In assembled form, as illustrated in Fig. 5, the shank 17 is only partially inserted into the yieldable sleeve 18 with the terminal 19 of the bridle-strap interposed between the 105 shank and sleeve. The shank 17 is of a larger diameter than the normal internal bore of the sleeve, while the external diameter of the sleeve is slightly less than the diameter of the opening 13 in the back stop. 110

It is thus obvious that the shank in partially inserted position in the sleeve facilitates

the initial insertion of the unexpanded end of the sleeve into the opening 13 of the back stop 11. When the sleeve is inserted, the shank 17 is forced further into the bore of the sleeve and the sleeve is forced through the opening 13 by an oscillatory movement preferably by inserting a screw driver in the kerf 21 of the headed element 16. After the sleeve is forced through the opening till the outer end of the same protrudes into the flared inner end 20 of the opening 13, the tip will assume the position illustrated in Fig. 3. The length of the sleeve and shank is such that the said sleeve will protrude beyond the inner end of the opening 13 to form a bulge 22 at this point, thereby securely anchoring the tip in place against accidental or casual withdrawal. The bulged portion 22 further serves as a yieldable buffering element in case the usual buffering element of felt has been lost. It is obvious that the attachment of the bridle-strap at this point in no way interferes with the usual functioning of the same and it will be further apparent that the time required for attaching the bridle-strap is reduced to an absolute minimum.

I claim:

30 1. A tip for attaching a bridle-strap to the back stop of a piano action comprising a pair of telescopically associated elements between which the terminal of the bridle-strap is clamped, said elements being insertable in the opening in the back stop.

35 2. A tip for attaching a bridle-strap to the back stop of a piano action comprising a pair of telescopically associated elements between which the terminal of the bridle-strap is clamped, said elements being insertable in the opening in the back stop, the outermost element being of a yieldable material and of slightly greater diameter than the diameter of the opening in the back stop.

40 45 3. An attaching tip for the bridle-strap of a piano action, comprising a member including a shank having a head at one end.

50 a yieldable sleeve telescopically arranged thereover with the terminal of the bridle-strap received therebetween, said tip in assembled relation being forcibly inserted in the opening in the back stop.

55 4. An attaching tip for the bridle-strap of a piano action, comprising a member including a shank having a head at one end, a yieldable sleeve telescopically arranged thereover with the terminal of the bridle-strap received therebetween, said tip in assembled relation being forcibly inserted in the opening in the back stop, the said sleeve at the end remote from the head adapted to protrude through the back stop opening whereby to expand and form an anchoring bulge.

60 65 5. The combination with the back stop of a piano action provided with an opening therethrough for the passage of the usual bridle-strap, of means for anchoring the terminal of the bridle-strap in the opening in the back stop comprising a member having a threaded shank provided with a head at one terminal, a yieldable sleeve embracing said shank, the outer diameter of which is greater than the diameter of the opening in the back stop shank, the terminal of the bridle-strap being clamped between the sleeve and shank, and sleeve, shank and bridle-strap terminal being forcibly inserted in the back stop opening.

70 75 80 85 90 95 6. A tip for attaching a bridle-strap to the back stop of a piano action, comprising a pair of telescopically associated elements between which the terminals of the bridle-strap is clamped, said elements being insertable in the opening in the back stop, the outermost element being of a yieldable contractible material which is adapted to be expanded by the innermost element to a diameter slightly greater than the diameter of the opening in the back stop at the point of protrusion of the free end of the outer element beyond said opening in the back stop.

CHARLES N. SCHNEIDER.
